(57) **CLAIM**

The ornamental design for a display screen or portion thereof with a graphical user interface as shown and described.

DESCRIPTION

This application is related to the following commonly owned co-pending patent application: U.S. application Ser. No. 29/878,628, entitled “Display Screen or Portion Thereof With a Graphical User Interface.”

The sole FIGURE is a front view of a display screen or portion thereof with a graphical user interface of our new design.

The dashed broken line perimeter in the drawings illustrate a display screen or portion thereof and forms no part of the claimed design.
